UNITED STATES PATENT OFFICE.

WILLIAM JAMES SARVIS, OF HANOVER, ONTARIO, CANADA.

STOVE.

1,133,747.

Specification of Letters Patent. Patented Mar. 30, 1915.

Application filed May 25, 1914. Serial No. 840,893.

To all whom it may concern:

Be it known that I, WILLIAM JAMES SARVIS, of the village of Hanover, in the county of Grey, in the Province of Ontario, Canada, have invented certain new and useful Improvements in Stoves, of which the following is the specification.

My invention relates to improvements in stoves and the object of the invention is to provide a stove which will draw the cold air from the fire level and utilize it for the up-draft through the fire and for controlling the up-draft in the stove chimney and it consists essentially of a right angular duct extending from the center of the stove bottom to the chimney side of the stove and from the center to the fire front side of the stove, an air supply orifice in the outer wall of the duct in proximity to the floor level, ducts extending vertically from the outer ends of the aforesaid ducts, openings in the inner wall thereof opening respectively into the ash space of the stove immediately beneath the grate and into the chimney in proximity to the ordinary draft opening and controlling dampers for such openings, as hereinafter more particularly explained by the following specification.

Figure 1, is a general perspective view of a stove with my invention applied thereto. Fig. 2, is a cross sectional view extending transversely through the fire pot and oven. Fig. 3, is a similar view to Fig. 2 taken at right angles thereto. Fig. 4, is a sectional detail of the means for controlling the position of the damper for regulating the size of the opening leading into the chimney.

In the drawings like letters of reference indicate corresponding parts in each figure. A is a stove body of any suitable construction, such body may be either a cast or sheet metal body. The stove A is provided with the usual oven space A', fire pot A² provided with a grate A³, ashpit space A⁴ and the flues A⁵, A⁶ and A⁷ leading around the oven and the direct draft opening A⁸ leading into the chimney and the opening A⁹ into the back flue also leading into the chimney.

The parts above described form the ordinary construction of the stove and I will now describe my device forming the subject matter of this invention.

B is a duct, the arms B' and B² of which are at right angles one to the other, the apex of the angle being located substantially in

the center of the stove bottom. The arm B' extends from the center of the stove bottom to the fire front of the stove and is provided with a vertical extension B³ extending upwardly to the grate level.

B⁴ is an opening formed in the common wall of the flue portion B³ and ashpit A⁴ opening at one side in the flue B³ and at the opposite side in the ashpit A⁴ immediately beneath the grate A³.

B⁵ is a flap damper pivoted above the opening B⁴.

B⁶ is a small opening formed in the front wall of the flue B³.

B⁷ is a push rod pivotally connected at its inner end to the flap damper B⁵ and passing toward its outer end through the opening B⁶. The lower edge of the push rod B⁷ is provided with a ratchet rack B⁸ designed to engage the lower edge of the opening B⁶ so as to hold the push rod B⁷ longitudinally in position and the damper B⁵ at the required angle. The arm B² of the flue B extends from the center of the stove bottom to the chimney side of the stove and to the back of the back flue formed between the back wall A¹⁰ of the oven and the back wall A¹¹ of the stove.

B⁹ is a vertical extension for the flue arm B², such extension extending vertically upwardly in proximity to the top of the stove and provided with an opening in the wall A¹¹ such wall forming the common wall between the duct portion B⁹ and the back flue of the stove. A¹² is the ordinary stove damper for controlling the draft through the direct draft opening A⁸.

B¹⁰ is a flap damper for controlling the passage of air through the opening leading from the vertical portion B⁹ of the duct B² to the chimney. B¹² is a slot formed in the stove top.

B¹³ is the operating crank of the damper B¹⁰.

B¹⁴ is a stem extending through the slot B¹² and provided at its upper end with a suitable knob B¹⁵ against which bears an arc-spring B¹⁶, the ends of the spring bearing upon the upper surface of the stove top.

B¹⁷ is a sliding plate carried by the stem B¹⁴ and adapted to close the slot B¹² in all positions of the stem.

B¹⁸ is a link connecting the lower end of the stem with the crank B¹³. It will thus be seen that by adjusting the position of the knob B¹⁵ and the stem B¹⁴ in the slot B¹²

that the position of the damper B^{10} may be readily adjusted.

B^{19} is an orifice formed in the lower wall of the ducts B and provided with an annular surrounding flange B^{20} projecting downwardly in close proximity to the floor.

B^{21} is the controlling arm for the ordinary direct damper A^{12} .

B^{22} and B^{23} are flue orifices and closures 10 therefor, by which the duct portions B' and B^2 may be cleaned when desired.

Having described the principal parts involved in my invention I shall briefly describe the operation of the same. It will be 15 readily seen that when the fire is once started in the fire pot A^2 that an up-draft through the fire is created from the ordinary up-draft damper A^{12} of the stove. When this has taken place the damper B^4 is 20 opened and the ordinary damper 2 of the stove entirely or partially closed. By this means the cold air from the floor is drawn to the fire through the opening B^{19} , the duct B' and duct portion B^3 through the 25 orifice B^4 and through the fire. If it is desired to limit the draft this may be done also by drawing the cold air from the floor through the other arm B^2 of the right angular duct and upwardly through the 30 passage B^9 and through the orifice B^{10} leading into the chimney, the admission of air

at a lower temperature to the air in the chimney checking the up-draft of hot air passing from the stove. When this is done of course, the duct damper A^{12} is closed, the 35 hot air passing around the oven and through the opening A^9 to the chimney. From this description it will be seen that I have devised a very simple device whereby the cold air may be drawn off from the floor and 40 utilized for creating the necessary up-draft through the fire thereby heating the air which is the coldest in the room and consequently raising the general temperature of 45 such room.

What I claim as my invention is.

In a stove, the combination with the stove body having the usual fire pot and chimney ducts and communicating flues, of a right angular duct extending along the bottom of 50 the stove from the center thereof and having an opening in the bottom wall, vertical branches upwardly from each end of the right angular duct, one vertical branch leading through a suitable opening into the 55 fire pot directly beneath the grate level and the other branch leading to the chimney duct, as and for the purpose specified.

WILLIAM JAMES SARVIS.
